Primary Examiner — Karen S Acker(74) *Attorney, Agent, or Firm* — Buchanan, Ingersoll & Rooney PC(57) **CLAIM**

The ornamental design for a mesh panel, as shown and described.

DESCRIPTION

FIG. 1 is a front, bottom perspective view of a mesh panel according to our new design.

FIG. 2 is a further front, bottom perspective view thereof.

FIG. 3 is a front elevational view thereof, the rear elevational view being a mirror image.

FIG. 4 is a bottom plan view thereof; and,

FIG. 5 is an enlarged left side elevational view thereof, the right side being a mirror image.
